DRAIN CLEANER

Claude Horwitz, Rose Bay, near Sydney, New South Wales, Australia

Application August 16, 1937, Serial No. 159,423
In Australia August 22, 1936

3 Claims. (Cl. 285—44)

This invention relates to improvements in means for freeing obstructions from waste pipes of sinks, drains and the like.

The blockage, or partial blockage, of sink, drain and the like waste pipes is a frequent source of nuisance and annoyance causing the sink or drain to flood with waste material of an insanitary and frequently disgusting nature. Heretofore the freeing of such blocked or partially blocked waste pipes has been a task requiring some considerable time thereby rendering any water supply situated above the associated sink or drain inoperative until the blockage has been disposed of. Such a task is invariably an unpleasant one and frequently the relief enjoyed is only temporary since the waste pipe is not completely freed from the obstructing material but merely a passage made through the obstruction of sufficient size to allow flow to ensue. As a result a further blockage is apt to occur after a comparatively short time.

Amongst the objects of the present invention are to produce a means for freeing blocked or partially blocked waste pipes of sinks, drains and the like which is simple, effective and rapid and which does not require the dismantling of any portion of the waste pipe system as has been the case heretofore.

The present invention relates to apparatus capable of firm and fluid-tight attachment to mouths of waste pipes of varying size and located at varying angles the said apparatus being adapted to receive a hose or pipe from a source of fluid supply such as an overhead tap, in such manner that a fluid-tight connection exists between the source of fluid supply and the waste pipe for the purpose of directing a head of fluid from the fluid source to the waste pipe so that the pressure thereof may impinge upon the obstruction in the waste pipe and thereby remove it. The connection between the source of fluid supply and the waste pipe concerned is capable of ready assembly or detachment.

In the drawing, which illustrates an approved form of the invention,

Figure 1 is a view showing the assembled device as applied to a sink,

Figure 2 is a vertical section through the device and through portion of a waste pipe,

Figure 3 is a sectional plan along the line 3—3 of Figure 2,

Figure 4 is a detail of the invention, and

Figure 4a is another view of the same detail.

With reference to the drawing, 15 is a source of fluid supply, such as a tap, to which is attached

a lead, such as a flexible hose 16, firmly attached to the tap 15 by means of a suitable union, such as the device designated generally by the numeral 17. The hose 16 is firmly attached at its lower end, as by a clamp 18, to a housing 10. 5 The housing 10 is adapted to be firmly attached to a waste pipe 11 by means of screw-threaded rods 12 bent or hooked at 13 to grip the grille 14 of the waste pipe 11. 20 is a band or ring provided with a medially disposed bar member 19 cast in or otherwise firmly attached to the band or ring 20. The bar member 19 is provided with slots 21 through which the screw-threaded rods 12 are adapted to project, 22 are washers and 23 nuts for the screw-threaded 15 rods 12.

The slots 21 are preferably comparatively wide to allow transverse movement of the rods 12 in order to accommodate them to grilles 14 of varying sizes. The bar member preferably includes 20 a spaced bridge piece 36 slotted at 37. This retains rods 12 with nuts 23 in association with the bar member when the device is not in use and prevents the rods 12 from slipping free. The tops 24 of the rods 12 may be wedge shaped and the wedge may point in the direction of the hooks 13 in order to show at a glance how the hooks 13 lie with regard to the grille 14. 25 is a central rod or shank adapted to be attached to the bar member 19. As shown in the drawing, the rod 30 25 is attached to bar member 19 by fixed rod 26 but it may be otherwise attached, as by screw-threading. The rod 25 is preferably allowed a small amount of lateral play at its base as shown at 38 and 39. This allows the housing 10 to be 35 located at a slight angle if necessary as when applying the device to a waste pipe orifice situated near the wall of a sink or basin. The bar 25, which is screw-threaded as shown at 27, passes through opening 35 in housing 10 and functions 40 to firmly attach housing 10 to the assembly through nut 28 impinging on washers 29 and 30. 30 is preferably a resilient washer. The base of the housing 10, which encircles ring or band 20, rides upon a resilient washer 31, suitably attached thereto as in a flange 32. 33 is a branch arm for the accommodation of the hose 16. 34 is a fragmentary detail of a sink or basin.

In operation band or ring 20 is placed about the orifice of the waste pipe 11 and rods 12 are 50 adjusted until they grip beneath the bars of grille 14 whereupon nuts 23 are tensioned to give a firm attachment of the rods 12 beneath the bars of the grille 14 so as to firmly attach the band or ring 20 about the waste pipe orifice. 55

If rod 25 is affixed to bar member 19 it will be already in position, otherwise it is located by screwing into bar member 19 or otherwise attaching it thereto. Rod 25 is preferably capable of slight lateral play to allow the housing 10 to be disposed at a slight angle in the case where the waste pipe orifice is located near the side wall of a sink or basin. Housing 10 is now placed about band or ring 20 and, in this position, rod 25 projects through opening 35 and receives washers 29 and 30 and nut 28. At this position resilient washer 31, located circumferentially of the base of the housing 10, surrounds the band or ring 20 and orifice of the waste pipe 11 and, upon tensioning of the nut 28, a fluid-tight joint is made by the resilient washer 31. Washer 30 is also of a nature adapted to form a fluid-tight seal. Hose 16 is attached at its upper end to tap 15 by suitable means, such as attachment 17, and at its lower end to branch arm 33, as by clamp 18. There now exists a direct fluid-tight channel from the tap to the waste pipe and, when the tap is turned on, the pressure head of water from the tap is applied directly through the waste pipe to the obstruction existing therein and by its force functions to remove the obstruction within a short space of time.

Having thus described and ascertained my said invention and the manner in which it is to be performed, I declare that what I claim as new and desire to secure by Letters Patent is:

1. Apparatus for flushing the outlets of sinks, drains and the like including an annular support for disposition on the outlet adjacent the outer edge thereof, a slotted bar member carried transversely of the support, waste pipe guard engaging hooks adjustably suspended from the slotted bar member for anchoring the support on the outlet, a rod operatively connected to the bar member, a casing closely surrounding the support and having water-tight engagement with the outlet and having an inlet adapted to receive a hose and having an opening in the top for engagement about the rod, and means detachably engaged about the projecting end of the rod for clamping the casing in water-tight engagement with the outlet.

2. Apparatus for flushing the outlet pipes of

sinks, drains and the like including an annular ring-like support for disposition on the mouth of the outlet pipe, a slotted bar member carried transversely and medially of the support, elongated and threaded waste pipe guard engaging hooks arranged in the slotted bar member, tensioning nuts engaged about the threaded portions of the hooks and with the bar member for maintaining the hooks in clamped engagement and for anchoring the support in position, a transverse and slotted bridge member carried with the top of the support and through which the upper ends of the hooks project for cooperating with the nuts and preventing accidental disengagement of the hooks when the device is not in use, a central stud integral with the bar member and the bridge member, a rod having its inner end pivotally connected to the stud and its outer extremity threaded, a casing closely surrounding the support having an inlet adapted to receive a housing and having an opening in the top for engagement about the threaded extremity of the rod, an annular sealing washer carried by the lower edge of the casing, and means detachably engaged with the threaded projecting end of the rod for clamping the casing in water-tight engagement with the outlet.

3. Apparatus for the purpose of enabling fluid pressure to be applied to the outlet pipes of sinks, drains and the like of the type wherein fluid is forced through a housing which is attached about the mouth of said outlet pipes characterized in that the housing is affixed in place by apparatus consisting of a ring, a medially disposed slotted bar member carried transversely of the ring, a slotted bridge carried with the ring above the bar member, adjustably mounted hook-ended screw threaded rods riding in the slots of said bar and bridge, tensioning nuts engaged with the rods and disposed between and retained against displacement by said bar and bridge, wedged tops on said rods pointing in the direction of the hooked ends thereof, and another rod pivotally attached centrally of said bar and bridge and having means on its upper end to tension it against the housing.

CLAUDE HORWITZ.
